poration, Hamilton, Ohio, a corporation of Vir-
ginia

Application August 8, 1945, Serial No. 609,625

8 Claims. (Cl. 29—26)

1

This invention relates to improvements in transmission and control mechanism for machine tools. More particularly, this invention pertains to an improved feed and rapid traverse control for a vertical boring mill.

One of the objects of this invention is to provide an improved transmission and control mechanism for the cutting tools of a vertical boring mill.

Another object is to provide an improved feed and rapid traverse transmission for a vertical boring mill which is readily adjustable for any desired operating condition with a minimum of effort and skill required on the part of the operator.

Another object of this invention is to provide an improved hydraulic servo operated tool actuating system for a vertical boring mill.

Still another object is to provide a hydraulic servo operated feed mechanism having infinitely variable feed adjustment together with a range selection adjustment.

Still another object is to provide a hydraulic servo operated actuating system for the cutting tools of a boring mill which may be readily adjusted for any desired feed or rapid traverse movement of the cutting tools.

Still another object of this invention is to provide a tool actuating system for a boring mill utilizing hydraulic servo power actuation and control for effecting the desired feed rate or rapid traverse movement, and stopping and starting of the tool movements.

A still further object is to provide, in a vertical boring mill, a hydraulic servo tool actuating system which receives its initial control power from the main source of power for actuating the work table.

And still another object is to provide an improved feed and rapid traverse control for a hydraulic servo operated tool actuating system.

It is also a further object to provide in conjunction with a hydraulic servo operated tool actuating system a vernier hand adjustment for accurate positioning of the tools in desired operation positions.

A further object is to provide a machine tool of large capacity which requires a minimum of floor space.

And an object is to provide exceptional ease of operation for a machine tool of large capacity.

And still another object of this invention is to incorporate a hydraulic servo operated feed and rapid traverse power transmission for the tools of a boring mill in the cross rail of the machine

2

and to operate the apparatus from the main source of driving for actuating the work table.

Further features and advantages of this invention will appear from the detailed description of the drawings in which:

Figure 1 is a front perspective view of a vertical boring mill incorporating the features of this invention.

Figure 2 is a plan view of the boring mill, partly in section on the line 2—2 of Figure 1.

Figure 3 is a front elevation of the feed rate and direction control levers on each end of the cross rail.

Figure 4 is a fragmentary left-hand end elevation of the feed and rapid traverse control box mounted on the rail as indicated by the line 4—4 in Figure 1.

Figure 5 is a fragmentary section on the line 5—5 of Figure 1 showing the main source of driving power for actuating the work table and the power take-off for operating the hydraulic servo tool actuating and control mechanism.

Figure 6 is a fragmentary section on the line 6—6 of Figure 1.

Figure 7 is a vertical section on the line 7—7 of Figures 1 and 2.

Figure 8 is a vertical section on the line 8—8 of Figures 1 and 2.

Figure 9 is an enlarged section view on the line 9—9 of Figures 1 and 11.

Figure 10 is an enlarged fragmentary section through a tool bar hydraulic servo control valve on the line 10—10 of Figure 1.

Figure 11 is a diagrammatic section on the line 11—11 of Figure 9.

Figure 12 is a fragmentary horizontal section on the line 12—12 of Figure 1.

Figure 13 is a section through the cross rail and actuating cylinders for the saddles on the line 13—13 of Figures 7 and 8.

Figure 14 is an enlarged view of the gearing shown in the direction indicated by the line 14—14 in Figures 6 and 11.

Figure 15 is a hydraulic circuit diagram associated with the tool control mechanism.

In modern machine tools, it is necessary to effect the control of the various movable machine elements with a high degree of accuracy and a minimum of physical effort required on the part of the operator in order to produce work of the desired high standard. This problem is particularly difficult in large heavy-duty machine tools because of the necessary great weight and sturdiness which must be built into the machine elements to produce the desired accuracy and

smooth finish on the work piece. Also in such modern machines, closer tolerances must be maintained between the various moving members of the machine such as the slide ways, bearings, and other relatively movable machine surfaces to obtain the desired high accuracy. As a result, former practices of direct mechanical actuation of the various machine members have been found impractical and unsatisfactory because of the large amounts of power and effort required on the part of the operator in making machine adjustments. It is therefore the purpose of this invention to minimize the effort required to operate the machine while providing the necessary great accuracy and nicety of control essential to a modern day machine tool.

As an example of a large machine tool of a heavy-duty type which this invention is particularly well adapted, there is illustrated a large vertical boring mill having a base 20, Figure 1, upon which is rotatably mounted the work table 21. On each side of the rotary work table 21 and rigidly secured to the base 20 are the upright columns 23 and 24 which are interconnected for rigidity by a suitable tie bar 25. On suitable guide ways 26 and 27 on the respective columns 23 and 24 is the vertically movable cross rail 28 which has horizontally extending guide ways 29, Figure 8, upon which is slidably mounted the saddles 30 and 31. These saddles carry swivel slides 30a and 31a upon which are slidably mounted the respective tool bars 32 and 33 on suitable guide ways 34, Figure 2, formed in the swivel slides.

Work table drive

The main driving power for rotating the work table 21 and for controlling the operation of the tool feeding devices is derived from a suitable prime mover or main drive motor 35, Figure 5, mounted on a suitable bracket 36 attached to the rear portion of the base 20. This motor which is preferably of a variable speed type, has a pinion 37 driving through a train of reduction gears 38, 39, 40, and 41, the main input power shaft 42. The shaft 42 which extends inwardly into the base 20 has a bevel gear 43 fixed to it which in turn drives a bevel gear 44 fixed to the vertically journaled pinion shaft 45 in the base 20. On the upper end of the shaft 45 is fixed the pinion 46 which meshes with the ring gear 47 on the work table 21 so that the application of electrical power to the motor 35 effects driving rotation of the work table 21 at a desired cutting speed.

Cross rail elevating mechanism

The cross rail 28 may be adjusted up and down to any desired position on the columns 23 and 24 by means of a suitable elevating mechanism which derives its power from an electric motor 48, Figures 1 and 8, mounted on the tie bar 25. This motor drives a worm 49 which actuates a worm wheel 50 fixed on the shaft 51 extending toward each column 23 and 24 where it is suitably journaled in the bevel gear boxes 52. The shaft 51 carries bevel gears 53 fixed on its ends which in turn engage mating bevel gears 54 fixed to suitable elevating screws 55 journaled against axial movement in the columns 23 and 24. Each of these screws operate in nuts 56, Figure 8, which are rigidly attached to the cross rail 28 so that by appropriately energizing the motor 48 for rotation in one direction or the other the cross rail may be moved up and down to any desired position.

Referring particularly to Figure 2, the rail clamping device which binds the rail in the desired selected position on the columns comprises a pair of opposed pistons 57 and 58 carried in a suitable cylinder 59 rigidly mounted on the cross rail 28. Each of these pistons have associated piston rods 60 on the outer ends of which are carried the actuating cams 61 which have a straight side 62 parallel to the direction of piston travel which rests against rollers 63 journaled on suitable studs 64 fixed in the cross rail 28. The tapered cam surface 65 engages the roller 66 on the lever arm 67 which is fulcrumed at the point 68 and has an abutting connection 69 with the column clamp 70 which engages the dove-tailed surface 71 of the columns 23 and 24.

In this arrangement fluid pressure may be alternately applied between the pistons 57 and 58 to effect unclamping or in the piston rod chambers of the cylinder to effect the clamping action. This may be accomplished readily by any suitable solenoid operated hydraulic control valve 72. When the solenoid 73 of the valve 72 is energized the valve connects fluid pressure from a fluid pressure pump 74, Figure 15, driven by a suitable motor 75 through the pressure lines 76 and branch line 76a to the chamber between the pistons 57 and 58 while the piston rod chambers behind these pistons are connected by the valve at this time through the line 77 to the drain line 78 which is connected to the fluid reservoir or tank 79 to effect unclamping. When the solenoid 73 is de-energized, the valve assumes a position wherein pressure from the lines 76 and 76a is now connected to the piston rod chambers while the drain lines 77 and 78 are connected to the chamber between the pistons for returning fluid to the tank to thus effect the clamping of the cross rail to the columns.

Hydraulic servo drive mechanism

The actuation and movement of the tool feeding devices comprising the saddles 30 and 31 and their respective tool bars 32 and 33 is accomplished by hydraulic fluid pressure means under servo control. The hydraulic servo control mechanism is actuated by mechanical power from the main drive motor 35, Figure 5. Power take-off from this motor comprises a bevel gear 80 in mesh with the bevel gear 44, this bevel gear being fixed on a suitable shaft 81 journaled in the base 20 upon which is also fixed a bevel gear 82, Figure 1. This bevel gear 82 in turn drives a bevel gear 84 fixed to a horizontally extending drive shaft 85 journaled in the base 20 of the machine and extending parallel to the cross rail 28 outwardly to each end of the machine. On the ends of this shaft 85 are provided the bevel gears 86 which in turn drive mating bevel gears 87 fixed to a vertical drive shafts 88 journaled at their lower ends in brackets attached to the base 20 of the machine and journaled in support brackets 89 fixed to the upper portions of the columns 23 and 24, these shafts serving to drive the feed control mechanism for the saddles and tool bars.

Feed and rapid traverse control

On each end of the cross rail 28 is provided the feed and rapid traverse control mechanism for operating the hydraulic servo device for the saddles and tool bars. The saddle 30 and its tool bar 32 are controlled in feed and rapid traverse movements by control mechanism mounted on the left-hand end of the cross rail while the

5

saddle 34 and its tool bar 33 are controlled by the apparatus on the right-hand end of the cross rail. Since the mechanisms at each end of the cross rail are substantially identical for operating their respective saddle and tool bar, it is sufficient to describe in detail but one of these arrangements.

Taking for example the feed and rapid traverse control unit on the end of the cross rail indicated generally at 98, power from the shaft 88 associated with the column 23 is transmitted to a bevel gear 91, Figure 11, journaled in a bracket 92 fixed to the cross rail 28, this bevel gear having a sliding driving connection with the shaft 88 so that it may be driven at all times for any vertical position of the cross rail on the columns. The bevel gear 91 in turn drives a bevel gear 93 fixed on the input drive shaft 94 of the feed and rapid traverse feed selector unit 95 fixed to the rear face 95a, Figure 12, of the left-hand end of the cross rail 28.

The shaft 94, in addition to being supported in a suitable bearing 96 in the bracket 92, is also journaled on suitable bearing 97 and 98 in the feed selector unit 95. On the shaft 94 is mounted the driving disc 99 so as to be at all times driven by the shaft 94 while it may be shifted axially thereof. A second shaft 100 is journaled on suitable bearings 101 and 102 coaxially with the shaft 94, this shaft carrying a friction disc 103, similar to that of the disc 99, which is adapted to drive the shaft 100 while it may be adjusted axially of the shaft 100.

Noting particularly Figure 9, both of the friction discs 99 and 103 are engaged simultaneously by a pair of friction plates 104 and 105 held in friction rolling contact therewith by a suitable compression spring 106 engaging by suitable means the journaled bearings 107 upon which the discs 104 and 105 rotate about the shaft 103 mounted in the unit 95. Each of the friction discs 99 and 103 are interconnected for simultaneous shifting movements radially of the discs 104 and 105 by means of the shifter yokes 109 and 110 fixed to the shifter rod 111 slidably mounted in the unit 95 so that axial movement of the rod 111 simultaneously varies the radial position of the friction discs 99 and 103 with respect to the plates 104 and 105 to effect infinite variations of speed in the shaft 100.

Power take-off from the shaft 100 is transmitted through the gear 112 to a gear 113 fixed to a shaft 114 journaled in suitable bearings 115 in the unit 95. Slidably mounted on the shaft 114 in keyed driving relationship therewith is a compound gear 116 having a large gear 117 and a smaller gear 118 which may be alternately engaged with the respective mating gears 119 and 120 fixed to a shaft 121 journaled in suitable bearings 122 in the unit 95. In this way, by shifting the compound gear 116 on the shaft 114, two ranges of speed may be effected in the shaft 121.

Power from the shaft 121 is transmitted by the gear 119 to a gear 123 journaled on the feed and rapid traverse clutch shaft 124 journaled in suitable bearings 125 in the unit 95. This gear 123 may be connected in driving relationship with the shaft 124 or disconnected therefrom by means of the feed clutch 126 which is operated by a suitable shifter spool 127. In this way, feed driving speeds may be applied to the shaft 124.

The shaft 124 may also be actuated at rapid traverse speed from a rapid traverse drive motor 128, Figure 4, suitably mounted on the unit 95.

6

and having a motor pulley 129 over which operates a suitable belt 130 which in turn drives a pulley 131 of the rapid traverse clutch 132, which is independently mounted to prevent rotational drag on the output shaft 124 but carried in axial alignment therewith. The rapid traverse clutch 132 may be actuated by its shifter spool 133 for connecting or disconnecting this rapid traverse driving power from the motor 128 to the shaft 124.

In this arrangement, the feed clutch 126 and the rapid traverse clutch 132 are alternately operated to connect the respective feed and rapid traverse power to the shaft 124 by means of the shifter yokes 134 and 135 respectively engaging the shifter spools 127 and 133, both of these yokes being fixed on the shifter rod 136 so that a single operating lever 177 may serve to disengage feed power and rapid traverse power to engage the feed power while retaining disengagement of the rapid traverse power, or engage rapid traverse power while maintaining disengagement of the feed power.

Power output from the shaft 124 is transmitted to the servo mechanism for the saddle through a pair of gears 137 and 138 fixed on the shaft 124. A slide gear 139 mounted in driving relationship on the saddle output shaft 140 may be directly engaged with the gear 137 to drive the shaft 140 in one direction of rotation. The shaft 140 may be driven in the opposite direction of rotation by engaging the gear 139 with a gear 141 of the double gear 142 journaled on a suitable shaft 142a in the unit 95, Figure 9, the other gear 143 of the double gear being in mesh with the gear 138 of the shaft 124.

Similarly, the output shaft 144 for the servo mechanism for the vertical movement of a tool bar may be connected to be driven in either direction from the shaft 124 by a gear 145 mounted in sliding driving relationship on shaft 144 for alternate engagement with the gear 137 on the shaft 124 or with gear 141 of the double gear 142.

There has thus been provided mechanism for stopping and starting and reversing either of the output shafts 140 or 144 for the respective saddle and tool bar servo mechanisms. There has also been provided a slow feed drive or a rapid traverse drive rate to the output shafts 140 and 144. A range of speed change for the feed drive to the shafts 140 and 144 is also provided by the shifting of the compound gear 116. Furthermore, there has been provided an infinitely variable feed rate change for the output shafts 140 and 144 by adjusting the friction discs 99 and 103 as described.

60 Control levers and indicating dials

In order to effect the infinitely variable feed rate change, the shifter rod 111, Figures 1, 4, and 9, is moved axially by means of its threaded portion 111a which operates in a nut 146 suitably journaled against axial movement in a bracket 95a of the feed selector unit 95. The nut 146 may be appropriately rotated by means of its integral bevel gear 147 which is engaged by a mating bevel gear 148 carried on the control knob shaft 149 journaled in the unit 95 and having on its outer end an operating knob 150 so that rotation of the knob rotates the nut 146 and thereby adjusts the friction discs 99 and 103 to effect the infinite variations in feed desired.

The feed range selection is made by means of the control lever 151, Figures 1, 3, and 4, which is carried on a suitable rock shaft 152 journaled in the unit 95 connected through suitable linkage 153 to a shifter rod 154 slidably mounted in the control box 95 and to which is connected the shifter yoke 155 engaging the compound gear 116. When the lever is moved to the position 151a, shown in Figure 3, the gears 118 and 120 are brought into mesh for a fine range of feeds, and when the lever is moved to the position 151b, Figure 3, the gears 117 and 119 are engaged for the coarse range of feeds.

Associated with the infinitely variable feed control knob 150 and the feed range control lever 151 is an indicating dial which at all times shows the exact rate of feed selected. This indicating dial comprises a disc 156 which is journaled on the knob shaft 149 and is driven at a reduced speed relative to the rate of rotation of the shaft 149 by its knob 150 by suitable reduction gearing comprising a pinion 157 fixed to the shaft 149 driving the large gear 158 of the compound gear 159 journaled on a suitable stud 160 fixed in the unit 95. The smaller gear 161 of the compound gear 159 in turn drives a gear 162 fixed to the dial 156.

On the dial 156, Figure 3, is an indicating pointer 163 which cooperates with graduations 164 provided on a ring 165 fixed to the outer face of the unit 95. The relationship of the pointer 163 to the graduations 164 when the control lever is in the coarse range feed position 151b, Figure 3, directly indicates the feed selected. When the lever 151 is moved to fine range position 151a, a pointer 166 on the ring 165 fixed to the unit 95 is associated with the fine feed range indications 167 on the rotating dial 156 so as to indicate the fine feed ranges selected by the control knob 150. By providing the control knob 150 with a self-locking feature, the sensitivity of the control is enhanced and by operating the indicating dial 156 at a reduced rotational speed relative to the knob 150, the entire feed range is brought to within a single revolution of the dial, thereby permitting reading directly the amount of feed per revolution of the table.

There has thus been provided an indicating dial device comprising fixed graduations on the machine frame and a rotating dial having graduations cooperating with a pointer on the machine frame for indicating one range of feed selection and having a pointer on the rotating dial cooperating with the fixed graduations on the machine for indicating another feed range selection.

The direction and stopping and starting of the saddle movement is accomplished by appropriately shifting the gear 139, Figure 11, by means of the saddle control lever 168, Figures 1, 3, and 4, carried on a rock shaft 169 appropriately journaled in the unit 95 and connected through suitable linkage 170 to the shifter rod 171 slidably mounted in the unit 95 and upon which is fixed the shifter yoke 172 appropriately connected to the gear 139. The lever 168 when in the position 168a causes the gear 139 to engage the gear 141 to apply power to the servo mechanism for the saddle to cause the saddle to move radially outward from the work table axis. When in the central or stop position 168b, the gear 139 is shifted to the neutral position shown in Figure 11 to arrest movement of the saddle. When the lever is in the position 168c, Figure 3, the gear 139 will engage the gear 137 to cause the saddle

to move radially inward toward the work table axis.

The tool bar vertical movement control lever 173, Figures 1, 3, and 4, is mounted on a suitable rock shaft 174 in the unit 95 and is connected by suitable linkage 175 and shifter rod 175a to a shifter yoke 176, Figure 9, which is connected to the gear 145 so that when the lever 173 is in the position 173a, the gear 145 will be in mesh with the gear 137 to cause the shaft 144 to rotate to drive the servo mechanism to effect upward movement of the tool bar. When the lever is moved to the stop position 173b, the gear 145 will be positioned in neutral as shown in Figure 11. And when the lever 173 is positioned at 173c, the gear 145 will be in mesh with the gear 141 to effect downward movement of the tool bar. Thus the control levers 168 and 173 serve to control the direction and stopping and starting movements of the saddle and tool bar.

The feed and rapid traverse movement is effected by means of the control lever 177, Figures 1 and 9, which is connected by a suitable lever arm 178 to a rock shaft 179 journaled in a depending bracket 180 carried on the unit 95. The rock shaft has a lever arm 181 connected to actuate the shifter rod 136 which simultaneously alternately engages the feed clutch 126 or the rapid clutch 132 or to render both of said clutches inoperative. This control lever has a rapid traverse position 177a in which the shifter rod 136 is moved to the right, Figure 11, to disengage the feed clutch 126 and engage the rapid traverse clutch 132 to effect rapid traverse rotation of the shaft 124. When the lever is moved to an intermediate or neutral position, 177b, both feed and rapid traverse clutches 126 and 132 are disengaged so as to arrest rotation of the shaft 124. When the control lever 177 is moved to the feed position 177c the rapid traverse clutch 132 is disengaged while the feed clutch is engaged to effect the slow speed drive to the shaft 124.

In this arrangement of the simultaneous control of the feed clutch and the rapid traverse clutch, the operator may rapidly move the control lever 177 through the neutral position in either direction to substantially instantly start or stop the rapid traverse or feed movement so as to effect a high degree of accuracy of control in instituting or stopping the rapid traverse and feed movements. He may also independently with this same lever 177 connect or disconnect feed motion independent of the rapid traverse motion or he may readily effect rapid traverse movements without instituting feed movements.

There has thus been provided a control mechanism for a hydraulic servo operated tool feeding system which incorporates an infinitely variable feed change and a range change for the feed drive, a direction and stop and start control, and a means for simultaneously or independently controlling the feed and rapid traverse movements of the servo operated mechanism. This feed and rapid traverse control provides, through the operation of the single lever 177, a constant speed of rapid traverse movement for rapid advance of the tool in the same direction as selected for feeding and independent of the speed of the feed setting. And it is to be further noted that since this control is driven from the main drive for the work table, the feed per revolution of the work table is maintained constant for any speed of rotation of the work table.

Servo screw and valve mechanism

Power for actuating the servo screw and valve mechanism for the horizontal movement of the saddle along the cross rail comprises a power take-off gear 182 fixed on the shaft 140, Figures 6, 11, and 14, which drives an idler gear 183 journaled on a suitable stud 184 carried in the cross rail 28. This idler gear in turn drives a gear 185 journaled on suitable bearings 186 and 187, Figures 6, 7, and 12, in a suitable bushing 188 fixed in the rail 28. Mounted for limited axial movement in the bore 185a of the gear 185 and adapted to be driven by the gear 185 through a suitable key 189 is a bushing 190 which is fixed to the servo operating screw 191 by a suitable pin 192 so that the screw may be rotated from the gear 185 while allowing it a certain limited amount of axial movement relative to the gear and cross rail.

The servo screw 191, Figures 6 and 12, serves to control the movement of the saddle 31 and is journaled in a bushing 193 in the gear 185 and is also supported in another guide bushing 194 fixed in the saddle 31. A nut 195 is also fixed in the saddle and is arranged in threaded engagement with the servo screw 191 so that rotation of the screw in the nut 195 causes this screw to move axially relative to the saddle 31.

The saddle 31 is actuated by a fluid pressure cylinder comprising the sleeve 196, Figure 14, rigidly mounted in the cross rail 28 so as to provide an integral rigidifying tubular member for the cross rail at its end portions where greatest strain and bending moments take place. The cylinder has a piston 197 to which is connected a piston rod 198 rigidly connected to the saddle 31 by suitable fastening nuts 199 at a point lying alongside of the other cylinder 197a so as to keep the over all length of the cross rail just long enough to accommodate the required extreme outward movement of the saddles 30 and 31.

Control of fluid pressure to the actuating cylinder 196 for the saddle 31 is provided by the servo control valve 200, Figures 6 and 15, which receives pressure from the pump 74 through the line 76 which is connected to the main pressure port 201 of the servo control valve 200. Ports 202 and 203 of the servo valve 200 are connected to the return or drain line 78 while the ports 204 and 205 of the valve 200 are respectively connected to the piston head chamber 206 and the piston rod chamber 207 of the saddle actuating cylinder 196.

The plunger 208 of the servo valve 200, which is connected to move axially with the movement of the screw 191, is provided with suitable annular grooves 209 and 210 of conventional servo valve arrangement which cooperate with the above recited ports to function as a reversing and rate of flow control valve as the plunger 208 is moved axially either side of the neutral position shown in Figure 6.

Assuming the saddle 31 to be stopped with the servo valve plunger positioned in neutral as shown in Figure 6, when power is applied to the gear 85 to rotate the screw 191, the screw will tend to be moved axially in one direction or the other, depending upon its direction of rotation, by its interaction with the nut 195 in the stationary saddle 31. However, as soon as the screw thus begins to move an appreciable distance axially, the servo valve plunger 208 will also thus be displaced from its neutral position and will cause fluid to be applied to the actuating cylinder 196 in such

a manner as to cause the saddle to move in opposite direction to the screw movement to bring the screw and the valve plunger 208 back to its neutral position. This automatic feed-back movement, which is typical of servo control mechanisms of this type, continues so long as there is relative axial adjustment of the screw 191 in the nut 195 relative to the saddle 31. This feed-back movement may take place in either direction depending upon the direction of rotation of the screw by the driving transmission as effected by shifting the gear 139, Figure 11, as described.

Thus, in this way, relatively small driving forces for rotating the servo screw 191 may effect powerful and accurate control through the actuating cylinder 96 for the saddle 31. A similar arrangement of a hydraulic actuating cylinder 196a having a piston 197a and a piston rod 198a connected to the saddle 30 at a point alongside the cylinder 196 serves to control the movement of this saddle by a suitable servo screw 191a and servo valve 200a as in the case of the saddle 31. The servo valve 200a is supplied by the pressure line 76b from the pump 74a and the drain line 78a appropriately connected by suitable lines 205a and 204a to the cylinder 196a.

Hand adjustment for the manual setting and accurate vernier positioning of the saddles 30 and 31 is provided by the hand wheels 211, Figures 30 1 and 12, which are journaled for free rotation on a shaft 212 journaled on suitable bearings 213 in the bracket 214 fixed on the saddles. The hand wheel may be clutched to the clutch teeth 215 of the clutch sleeve 216 fixed to the shaft 212 so as to rotate this shaft and a bevel gear 217 fixed on its inner end which engages the mating bevel gear 218 carried on suitable bearings 219 against axial movement in the saddle 31. The bevel gear 218 is provided with a keyed bore to 40 permit axial sliding of the screw when driven by rotation of the hand wheel 211. A compression spring 220 serves to normally disengage the hand wheel 211 from the clutch sleeve 216 so that it will not rotate when the servo screw 191 is being driven by the power feed or rapid traverse drive.

The same mechanism shown in Figure 12 is utilized for the left-hand saddle 30 and will therefore need no further description in that connection.

It is to be clearly noted that the cross rail arrangement, including the hydraulic actuating cylinders for moving the saddles 30 and 31 thereon, is of unique and novel construction. Heretofore, it has been considered impractical to provide direct hydraulic actuation of the saddles on the cross rail of a boring mill due to necessary space limitations and structural rigidity required in the boring mill. Applicant, however, by a unique arrangement of the essential hydraulic operating and control elements for the saddles on the rail, has provided a rail structure which requires no more floor space than in conventional mechanically actuated machines and which rail need only be long enough to accommodate the actual maximum movement of the saddles to their outermost positions relative to the work table axis.

In order to accomplish these desirable results with hydraulic actuation of the saddles, the cylinders 196 and 196a, Figure 13, are arranged in an overlapping manner so that their respective piston rods operate alongside of the respective cylinders where they are connected to the saddles 30 and 31 as best seen in Figure 13. It is to be noted that these cylinders are spaced one above the other, Figures 7 and 8, so as to provide a mini-

imum of outward overhand for the rail and saddles with respect to the columns to thereby increase the over all rigidity of the tool holding structure.

Another important feature of this arrangement is that of mounting the cylinders 196 and 196a directly in the rail casting. The object of this arrangement, in addition to minimizing the over all dimensions of the rail, is to provide steel tubes serving as the actuating cylinders for the saddles which also act to add rigidity to the rail at each end where the greatest bending movement and strain are present in the rail under operating conditions. Thus, in this unique arrangement of staggered or overlapping cylinders, with cylinders mounted integrally with cross rail casting, a minimum of space is required for the machine while at the same time providing great rigidity in the cross rail.

The drive for actuating the vertical servo control valves 221 and 222 for the respective tool bars 32 and 33 is derived from the output gear 223 fixed to the shaft 144, Figures 6, 11, and 14, which in turn drives an idler gear 224 appropriately journaled on the stud 184 fixed in the rails 28. This idler gear in turn drives a gear 225 fixed on a shaft 226 journaled in the rail 28. A bevel gear 227 is journaled against axial movement in the saddle 31 and surrounds the shaft 226 in driving engagement therewith and axially slidably there along upon movement of the saddle along the cross rail. The bevel gear 227 in turn engages a bevel gear 228 having a spur gear 229 attached thereto and journaled on a suitable stud 230 fixed in the saddle 31. The gear 229 in turn drives a gear 231 fixed on a shaft 232 journaled about the center of swiveling of the swivel slide 31a which is held to the saddle 31 by appropriate bolts operating in the T-slots 234 in a conventional manner.

On the end of the shaft 232 is fixed the bevel gear 235 which in turn meshes with the bevel gear 236 fixed to the shaft 237 journaled in the swivel slide 31a. The upper end of the shaft 237 is provided with a gear 238 which in turn drives a gear 239 of the servo screw operating nut 240 journaled against axial movement in the swivel slide 31a. When the nut 240 is rotated by the gear 239 to axially translate the servo screw 241 relative to the swivel slide 31a, the valve plunger 242 for the servo valve 222, which is connected to the screw 241, is moved axially as in the case of the plunger 208 of the valve 200, Figure 6. Pressure is supplied to the valve 222 from the pump 74 through the line 76 and the branch line 243 while a return flow from the discharge ports 244 and 245 are connected to the drain lines 246 and 78 for return of fluid to the reservoir 79. Suitable lines 247 and 248 are connected to the vertical cylinder 249 fixed in the swivel slide 31a. A piston 250 is mounted in this cylinder and has a piston rod 251 connected to the bracket 252 which in turn is secured to the tool bar 33. A feed-back connection between the bracket 252 and the servo screw 241 and servo valve plunger 242 is provided by the arm 254 which is rigidly connected to the upwardly projecting rod 255 from the servo valve plunger 242.

This mechanism functions similarly to that of the mechanism described for actuating the saddles 30 and 31 except that axial movement of the plunger in the servo valve 222 is effected by rotating the nut 240. The nut 240 has a suitable threaded portion 240a driving the nut and cooperating with the screw 241, the portion 240n having limited axial movement relative to the

nut 240. The threaded portion 240n is attached to the servo valve plunger 242 through which the screw 241 freely passes, the screw being rigidly attached to the bracket 252 of the tool bar 33 as described. Thus rotation of the nut 240 causes axial displacement of the servo valve plunger 242 from a neutral position in that axial movement of the servo screw 241 as effected by rotating the nut 240 causes the valve plunger 242 of the servo valve 222 to be axially displaced from the neutral position, shown in Figure 10, to cause fluid pressure to be applied to the cylinder 249 to effect movement in the tool bar 253. The movement of the tool bar restores the valve plunger 242 to its neutral position through the servo feed-back linkage 254 as in conventional servo control mechanism of this type.

Similarly the tool bar 32 on the saddle 30 is controlled by the servo valve 221, Figure 15, which receives fluid pressure from the line 76b and the branch line 256 and returns fluid through the drain line 257 through the line 78 to the fluid reservoir 79. Appropriate lines 247a and 248a interconnect the servo valve 221 and the cylinder 249a so that operation of the servo plunger 242 by actuation of its operating nut 240a on the screw 241a similarly effects movements in the tool bar 32, the feed-back control again taking place through a similar bracket 252a and arm 254a interconnecting the piston rod 251a and piston 250a with the tool bar 32 and servo screw 241a.

A manual vernier adjustment of the vertical position of the tool bars may be effected by hand wheels 256, Figure 1, arranged to rotate the shafts 226 and 226a in the same manner as the servo screw 191 is manually rotated as described in Figure 12.

Operation

The preferred manner of using the machine is as follows: The operator first mounts a work piece to be machined on the work table 21 by suitable clamps or chuck fixtures as is conventional practice in such machines. The hydraulic system of the machine is then put in operation by energizing the driving motor 75 for the fluid pressure pumps 74 and 74a. The rapid traverse drive motors 128 on the cross rail 28 are energized and put in continuous operation. Cutting tools, suitable to perform the desired machining operations on the work piece mounted on the table, are placed in tool holders on the tool bars 32 and 33 in a conventional manner.

The cross rail 28 is then located in proper position relative to the work piece on the table 21 by energizing the solenoid 73 of the rail clamp control valve 72 to unclamp the rail from the columns 23 and 24. The rail elevating motor 48 may then be energized in one direction or the other for raising and lowering the rail to desired operating position. After the rail has been positioned, the solenoid 73 is again de-energized to cause fluid pressure to again clamp the rail to the columns as described.

The work table 21 is then rotated by energizing the main drive motor 35. The saddles 30 and 31 may each be independently moved relative to the work on the work table 21 at rapid traverse movement to initially bring the tools up to proper cutting position with the work piece by positioning the control levers 168 for the desired direction of in or out travel of the saddles and moving the feed and rapid traverse control levers 171 to positions 171b to initiate the rapid traverse

movement in the direction determined by the levers 168. The tool bars 32 and 33 carrying the cutting tools are positioned by rapid traverse movement in proper cutting relationship to the work piece by placing the control levers 173 in the correct position of direction of travel and operating the feed and rapid traverse control levers 177.

Having thus initially brought the tools to proper initial starting position for a cut on the work piece, the operator then selects the desired feed rate suitable for the material to be cut by adjusting the feed range control lever 151 and the infinitely variable feed adjusting knob 150 at each end of the cross rail 28. Having thus selected the proper feed rate and having determined the direction of saddle or tool bar movement by positioning the respective levers 168 and 173 in the correct positions, the feeding of the tool over the work piece during rotation of the work spindle 21 may be accomplished by moving the feed and rapid traverse control levers to feed position 177c. The feed and rapid traverse movement may be stopped at any time by moving the control lever 177 to position 177b of neutral or nonmovement of the respective saddles and tool bars relative to the work spindle 21. The levers 168 and 173 may also be operated to independently or simultaneously stop or reverse the saddles and tool bars.

The saddles and tool bars may be fed manually by manipulating the control hand wheels 211 and 256 when carefully controlled feeding conditions are required for feeding the tool up against a shoulder or abutment on the work piece. The indicating dials 213 serve to show to the operator the depth of feed and distance his tool has traveled relative to the work for effecting proper sizing of the finished machine work surface.

After the machining operations on the work piece on the table 21 have been completed, the operator may readily retract the cutting tools from the work by actuating the tool bars 32 and 33 and the saddles 30 and 31 in rapid traverse movements by appropriately positioning the control levers 173 and 168 in the direction of travel desired and manipulating the feed and rapid traverse control lever 177 to the rapid traverse position 177c. The main drive motor 35 may be de-energized to stop the work spindle 21 for removal of the work piece and replace it with a new unmachined work piece. To completely render the machine inoperative, the main drive motor 35, the hydraulic system fluid pressure pump motor 75, and the rapid traverse drive motors 128 are de-energized.

It is to be noted that the rapid traverse drive motor 128 may be continuously operated independent of the operation of the main drive motor 35 so that rapid traverse movement may be readily effected in the saddles and tools for initially positioning them relative to work even though the work spindle is stopped and the main drive motor de-energized and the feed thereby rendered inoperative. Thus, the operator may initially position his tools by rapid movement up to the work while the work is stationary for proper setting of the tools with respect to the work surface to be machined.

Considering the operation of the tool feeding devices in specific detail: When the operator wishes to effect the horizontal cross feeding of the saddles 30 or 31 to perform a radial facing cut perpendicular to the axis of rotation of the work table, he first positions the saddle control

lever 168 in the position 168c if he wishes to feed inwardly toward the work table axis, or in the position 168a if he wishes to feed outwardly in a facing cut. Having thus positioned the saddle 5 actuating lever in one position or the other for in and out feed and having positioned the tool bar control lever 173 in the stop position 173b, and assuming he has also appropriately adjusted the feed rate by manipulation of the control knob 150 and 151 as described for the character of the metal and nature of the cut to be taken, he may then institute the feed movement in the set direction at either feed or rapid traverse movements by operating the control lever 171 to the 15 171a position for rapid traverse movement or to the position 171c for the feed movement. The feed or rapid traverse movements may be stopped at any time by moving the control lever 171 to neutral position. In this way, the horizontal radial facing cuts are made on the work by feeding the saddles along the rail into or away from the center of the work table as the work piece is being rotated thereby under the cutting tool carried on the tool bar 33.

20 When it is desired to do turning or boring operations by the vertical reciprocation of the tool bar 32 or 33, the control levers for the saddle 168 are positioned in the neutral stop position 168b while the vertical tool bar movements are controlled upwardly by moving the lever 173 from the stop position to the up position 173a or to the down position 173c. Again the feeds selected for the vertical tool bar turning or boring movements are selected by appropriately adjusting the control knob 150 and its associated lever 151. Here again the vertical feed and rapid traverse movements for the tool bars may be controlled under these conditions by again manipulating the control lever 177 to the position 177a for rapid upward or downward movement, depending upon the setting of the control lever 173, or at feed movements in up and down direction. Thus, if the operator wishes to effect a downward turning or boring cut with the tool bar 33, for example, he positions the lever 173 in the position 173c and then manipulates the feed and rapid traverse control lever 177 either to the rapid traverse position 177a or to the feed position 177c. Likewise, the upward movements are similarly effected by repositioning the lever 173 up to the position 173a and continuing the control of the tool bars in upward feed and rapid traverse movements by the lever 177.

45 Thus, the operator has full selective control of all facing, turning, and boring cuts for the saddle and tool bars by the proper setting of the selector reversing clutch control levers 168 and 173 and controls the application of feed and rapid traverse power in the selected direction effected by these levers by manipulation of the control lever 177.

50 While the apparatus herein disclosed and described constitutes a preferred form of the invention, it is to be understood that the apparatus is capable of mechanical alteration without departing from the spirit of the invention and that such mechanical arrangements and commercial adaptations as fall within the scope of the appended claims are intended to be included therein.

55 Having thus fully set forth and described this invention, what is claimed as new and desired to be secured by United States Letters Patent is:

60 1. In a vertical boring mill having a frame, a rotary work table on said frame, and a cross

rail on said frame associated with said work table, a pair of tool carrying saddles movable in facing feed movements radially of the axis of said work table on spaced guide ways on said rail, hydraulic actuating means for moving said saddles in said facing feed movements comprising a pair of hydraulic cylinders rigidly mounted inside of said rail between said guide ways to form integral strengthening members for said rail, pistons in said cylinders, piston rods, connected to said pistons, each extending along the side of the other cylinder, and means connecting said piston rods to said saddles so that fluid pressure applied in said cylinders effects said facing feed movement of said saddles on said rail.

2. In a vertical boring mill having a horizontally disposed cross rail, a pair of saddles movable on guide ways on said rail in radial facing feed movement relating to the axis of said work table, a hydraulic actuating cylinder for moving each of said saddles in said facing feed movement each comprising a cylinder sleeve mounted inside of each end of said cross rail so as to provide an integral rigidifying member for said rail, piston and piston rod means operable in each of said cylinders, and means for connecting said piston rods to said saddles at a point in said rails between said guide ways alongside of said cylinders so as to reduce the over all length of said rail.

3. In a machine tool having, a rotary work holder, a cross rail, a pair of tool carriers movably mounted on spaced guide ways on said rail for radial facing feed movement relative to the axis of rotation of said work holder, and fluid pressure actuating means for said tool carriers comprising a pair of cylinders one mounted inside each end of said rail between said guide ways, pistons including piston rods operably mounted in said cylinders, and means including control mechanism interconnecting each of said tool carriers to be operated by one of said cylinders, said last mentioned means being located in said rail alongside each of said cylinders.

4. In a vertical boring mill structure including a cross rail, tool carrying saddles horizontally slideable in facing feed movement on guide ways on said rail, and fluid pressure actuating means for moving said saddles in facing feed movement comprising a pair of hydraulic cylinders including a cylinder sleeve mounted inside of each end of said rail for increasing the rigidity thereof, said cylinders having their axes lying in a vertical plane disposed parallel to the direction of facing feed movement of said saddles and located between said guide ways, and means including a piston and a piston rod in each of said cylinders connected to said saddles alongside of said cylinders so that the application of fluid pressure in said cylinders effects movement of said saddles.

5. In a vertical boring mill having a frame, a rotatable work table on said frame, and a cross rail associated with said work table, a pair of tool carrying saddles mounted on guide ways on said cross rail for facing feed movement radially of the axis of rotation of said work table, and means for actuating said saddles in facing feed movement and strengthening said rail comprising a pair of cylinder sleeves rigidly mounted one inside each end of said rail between said guide ways serving to rigidify said portions of said rail, pistons including piston rods operably mounted in said cylinder sleeves, and means located between said guide ways including control mechanism for operably connecting each of said piston rods to one of said saddles each side of the other

cylinder sleeve, and fluid pressure means connectable to said cylinders to effect movement of said saddles on said rail.

6. In a vertical boring mill having a frame, a rotary work table on said frame, and a cross rail on said frame associated with said work table, a saddle movable on said rail in radial facing feed movements relative to the axis of rotation of said work table, a saddle actuating cylinder connected to move said saddle, a tool bar movably mounted on said saddle for longitudinal turning and boring movements parallel to said axis of the work table, a tool bar actuating cylinder connected to move said tool bar, and a main drive motor connected to rotate said work table, the combination of a source of fluid pressure, a saddle servo valve interconnected between said source of fluid pressure and said saddle actuating cylinder, a tool bar servo valve interconnected between said source of fluid pressure and said tool bar actuating cylinder, and power means for reversibly selectively actuating said servo valves in feed and rapid traverse rates or to arrest their actuation comprising a feed rate changer driven from said main drive motor, a source of rapid traverse drive power, a feed and rapid traverse clutch device driven from said feed rate changer and said source of rapid traverse drive power, a control lever for said clutch device operable to feed, rapid traverse, and neutral positions to effect feed and rapid traverse output from said clutch device or to arrest output from said clutch device, a saddle reversing clutch and a tool bar reversing clutch each connected to the output from said feed and rapid traverse clutch device, control lever means for each of said reversing clutches, and a mechanical drive connection from said saddle reversing clutch to the saddle servo valve and from said tool bar reversing clutch to said tool bar servo valve.

7. In a vertical boring mill having a frame, a rotary work table on said frame, and a cross rail on said frame associated with said work table, a saddle movable on said rail in radial facing feed movements relative to the axis of rotation of said work table, a saddle actuating cylinder connected to move said saddle, a tool bar movably mounted on said saddle for longitudinal turning and boring movements parallel to said axis of the work table, a tool bar actuating cylinder connected to move said tool bar, and a main drive motor connected to rotate said work table, the combination of a source of fluid pressure, a saddle servo valve interconnected between said source of fluid pressure and said saddle actuating cylinder, a tool bar servo valve interconnected between said source of fluid pressure and said tool bar actuating cylinder, and power means for reversibly selectively actuating said servo valves in feed and rapid traverse rates or to arrest their actuation comprising a feed rate changer driven from said main drive motor, a source of rapid traverse drive power, a feed and rapid traverse clutch device driven from said feed rate changer and said source of rapid traverse drive power, a control lever for said clutch device operable to feed, rapid traverse, and neutral positions to effect feed and rapid traverse output from said clutch device or to arrest output from said clutch device, a saddle reversing clutch and a tool bar reversing clutch each connected to the output from said feed and rapid traverse clutch device, a control lever for said saddle reversing clutch having in and out and stop positions, a control lever for said tool bar reversing clutch having up

and down and stop positions, and a mechanical servo feed back drive connection from said saddle and tool bar reversing clutches respectively to the saddle and tool bar reversing valves.

8. In a vertical boring mill having a frame, a rotary work table on said frame, and a cross rail on said frame associated with said work table, a saddle movable on said rail in radial facing feed movements relative to the axis of rotation of said work table, a saddle actuating cylinder connected to move said saddle, a tool bar movably mounted on said saddle for longitudinal turning and boring movements parallel to the axis of rotation of said work table, a tool bar actuating cylinder connected to move said tool bar, and a main drive motor connected to drive said work table, the combination of a fluid pressure pump, a motor for driving said pump, a saddle servo valve interconnected between said pump and said saddle actuating cylinder, a tool bar servo valve interconnected between said pump and said tool bar actuating cylinder, and power means for reversibly and selectively actuating said servo valves at varying rates of feed and at a rapid traverse rate or to stop actuation of said valves comprising a variable feed rate transmission driven from said main drive motor, an independent continuously operating rapid traverse motor, a feed and rapid traverse clutch device connected to be driven from said transmission

30

and said rapid traverse drive motor, a control lever for said clutch device operable to feed, rapid traverse, and neutral positions for applying feed and rapid traverse output drive from said clutch device or to arrest output therefrom to a saddle reversing clutch and to a tool bar reversing clutch each connected to the output of said rapid traverse clutch device, and a control lever means associated with each of said saddle and tool bar reversing clutches operable to disconnect power from said feed and rapid traverse clutch device or to reversibly apply said power respectively to the saddle servo valve and said tool bar servo valve through a mechanical servo feed back drive adapted to actuate the respective servo valves.
